UNITED STATES PATENT OFFICE

2,646,937

TEXTILE APPARATUS

Elmer L. Johnson, Pearisburg, and Carl R. Dela-grange, Ripplemead, Va., assignors to Celanese Corporation of America, New York, N. Y., a corporation of Delaware

Application June 23, 1949, Serial No. 100,862

15 Claims. (Cl. 242—35.5)

1

This invention relates to textile apparatus and relates more particularly to textile apparatus wherein a plurality of yarn packages are wound simultaneously and doffed in predetermined order.

In the production and processing of filamentary materials, such as yarns, threads, cord, etc., hereinafter called yarns, it is customary to wind simultaneously a plurality of yarns, as they leave the apparatus in which they are formed or treated, onto a plurality of yarn packages. If the feed of yarns to the winding apparatus is continuous for a period of time longer than is required to fill a yarn package, as in the production of artificial yarns, the yarn packages must be doffed after a predetermined quantity of yarn has been wound thereon. It has heretofore been the practice to have an operator periodically doff a group of yarn packages in predetermined order, in which case unavoidable differences arise in the quantity of yarn on the yarn packages owing to the variations in the time required for the operator to doff each yarn package. Since the variations in the doffing time may be cumulative, these differences may be quite appreciable when a large number of yarn packages are doffed. Such differences are highly objectionable, particularly when the yarns from the yarn packages are to be formed into a warp, since all the yarn packages must be replaced when the yarn has been drawn completely from the package having the smallest quantity of yarn thereon. In an effort to prevent the production of yarn packages of varying yarn content, it has previously been proposed to provide means for indicating when each yarn package is ready for doffing. However, it has been found that the operator often fails to or cannot keep abreast of the indicating means and, as a result, differences in the quantity of the yarn wound on the yarn packages still occur.

It is an important object of this invention to provide a textile apparatus having means for simultaneously winding a plurality of yarn packages, which will be free from the foregoing and other disadvantages of prior apparatus and which will be especially simple in construction and efficient in operation.

A further object of this invention is the provision, in a textile apparatus having means for simultaneously winding a plurality of yarn packages, of means for automatically stopping the winding operation of the yarn packages in predetermined order when the yarn packages are ready to be doffed.

Other objects of this invention, together with

2

certain details of construction and combinations of parts, will be apparent from the following detailed description and claims.

In accordance with our invention, a textile apparatus having means for simultaneously winding a plurality of yarn packages has associated therewith means for automatically stopping the winding operation of a group of yarn packages in predetermined order when the yarn packages are ready to be doffed, whereby the production of yarn packages containing different amounts of yarn thereon is substantially prevented. The means for automatically stopping the winding operation of the group of yarn packages may be caused to operate periodically by a timing mechanism, which is set in accordance with the winding speed to produce yarn packages containing the desired quantity of yarn thereon. In addition, the timing mechanism may actuate a signal means to advise the operator that the doffing of a group of yarn packages is to begin and also give warning if the operator fails to attend the textile apparatus within a predetermined period of time thereafter. By the application of this invention, erratic doffing is eliminated, resulting in an improvement of the quality of the finished yarn packages due to the uniformity of the package weights.

A preferred embodiment of our invention is illustrated in the accompanying drawings wherein

Fig. 1 is a front elevational view of a filament spinning apparatus to which our invention is applied,

Fig. 2 is a side elevational view of the apparatus shown in Fig. 1, and

Fig. 3 is a schematic diagram of the circuit for the timing mechanism, signal means and warning means.

Like reference numerals refer to like parts throughout the several views of the drawings.

Referring now to the drawings, the reference numeral 11 designates each of a plurality of spindles, which spindles are driven by any suitable means (not shown) and upon which are mounted bobbins 12 to receive a winding of yarn. Each of the spindles 11 is provided, in a manner well understood in the art, with a spindle brake that is actuated by a brake handle 13 which is normally manually operated to stop the rotation of the spindle and the bobbin 12 mounted thereon.

Mounted below the spindles 11 is an endless belt such as an articulate chain 14 to which travellers 15 and 16 are fastened at points spaced

apart a distance equal to one-half the length of the chain. The chain 14 is trained around a driving sprocket 17 and an idler sprocket 18 and is supported throughout its length by slotted pipes 19 that prevent the chain from sagging. An electric motor 21 drives the chain 14 through a speed reducer 22 and a gear train including a gear 23 fastened to the speed reducer 22, a gear 24, which is meshed with the gear 23, a gear 25 fastened to the gear 24, and a gear 26 which is 10 meshed with the gear 25 and which is fastened to the driving sprocket 17.

As the chain 14 moves, it carries the traveller 15 to the left and into contact with a lever 27 that is fastened to a hinge 28 mounted on an angle-iron support 29. The continued motion of the traveller 15 exerts an upward pressure on the lever 27, which causes said lever to impose a downward force on the spindle brake handle 13, causing the spindle brake to stop the rotation of the spindle 11 and the bobbin 12 mounted thereon. When the spindle 11 stops, the operator doffs the bobbin 12 and replaces it with an empty bobbin. The traveller 15 then passes beyond the end of the lever 27 releasing the spindle brake and permitting the spindle 11 with the empty bobbin 12 thereon to rotate once more, at which time the operator engages the yarn with the empty bobbin 12 so that the winding operation is resumed.

The continued motion of the traveller 15 then carries it into contact with the next lever 27 where the entire cycle is repeated. The operator keeps abreast of the traveller 15 and his individual skill may be accommodated by adjusting the speed of the chain 14. When the traveller 15 has been carried the full length of the spinning machine, it contacts a limit switch 30, which causes the motor 21 to be stopped. At this time, the traveller 16 is in the proper 40 position to initiate the next cycle. When a very large number of spindles 11 are operated in a single line, limit switches similar to the limit switch 30 may be provided to stop the traveller 15 at one or more intermediate points. This makes it possible to time the doffing operation so that there can be rest periods for the operator during the process of doffing a complete machine.

The operation of the motor 21 is controlled by an adjustable timer 31 that is connected across a power line 32. At predetermined intervals, depending upon the winding speed and the total quantity of yarn to be wound on each of the bobbins 12, the timer 31 operates a relay 33, energizing a starter 34 to connect the motor 21 to a power line 35. The operation of the relay 33 also causes pilot lights 36 and 37, which may be located at the spinning machine and at a central control point, respectively, to light and sounds a horn 38 as a signal that doffing is to begin. At the same time, an interval timer 39 is energized. The relay 33 is equipped with a holding coil so that current continues to flow through the pilot lights 36 and 37, the horn 38 and the interval timer 39 until the operator depresses a push button switch 41 located at the spinning machine to signify that he is in position to begin doffing. If, however, the operator fails to depress the push button switch 41 within a predetermined interval after the relay 33 is closed, the contacts of the interval timer 39 close, energizing warning lights 42 and 43, which may be located at the spinning machine and at a central control

75

point, respectively, and causing a warning horn 44 to sound. As shown, the limit switch 30 is connected to the starter 34 and upon being opened causes the motor 21 to be stopped.

It is to be understood that the foregoing detailed description is given merely by way of illustration and that many variations may be made therein without departing from the spirit of our invention.

Having described our invention, what we desire to secure by Letters Patent is:

1. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles.
2. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles, and timing means for periodically initiating the action of said automatic means.
3. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles, and signal means for indicating that the action of the automatic means for halting the rotation of said spindles is to begin.
4. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles, timing means for periodically initiating the action of the means for halting the rotation of said spindles, and separate signal means for indicating that the action of the means for halting the rotation of said spindles is to begin.
5. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles, and warning means including an interval timer for indicating that the textile apparatus is unattended after rotation of a spindle has been halted by the operation of said automatic means.
6. In a device for simultaneously winding a plurality of yarn packages, the combination with a plurality of spindles for supporting and rotating the yarn packages and a frictional contact spindle brake for each spindle, of automatic means for operating on said spindle brakes in predetermined order to cause the latter to halt the rotation of said spindles, timing means for periodically initiating the action of the means for halting the rotation of said spindles, signal

means for indicating that the action of the means for halting the rotation of said spindles is to begin, and warning means including an interval timer for indicating that the textile apparatus is unattended after rotation of a spindle has been halted by the operation of said automatic means.

7. In a device for simultaneously winding a plurality of yarn packages, the combination with a plurality of spindles for supporting and rotating the yarn packages and a spindle brake for each spindle, of an endless belt positioned to pass adjacent to said spindles, and a traveller fastened to said belt for operating on said spindle brakes in predetermined order to cause the latter to halt the rotation of said spindles.

8. In a device for simultaneously winding a plurality of yarn packages, the combination with a plurality of spindles for supporting and rotating the yarn packages and a spindle brake for each spindle, of an endless belt positioned to pass adjacent to said spindles, and a pair of travellers fastened to said belt at points spaced apart a distance equal to one-half the length of said belt, said travellers operating on said spindle brakes in predetermined order to cause the latter to halt the rotation of said spindles.

9. In a device for simultaneously winding a plurality of yarn packages, the combination with a plurality of spindles for supporting and rotating the yarn packages and a spindle brake for each spindle, of an endless belt positioned to pass adjacent to said spindles, a traveller fastened to said belt for operating on said spindle brakes in predetermined order to cause the latter to halt the rotation of said spindles, a drive for moving said belt relative to said spindle and a timer for periodically starting said drive.

10. In a device for simultaneously winding a plurality of yarn packages, the combination with a plurality of spindles for supporting and rotating the yarn packages and a spindle brake for each spindle, of an endless belt positioned to pass adjacent to said spindles, a traveller fastened to said belt for operating on said spindle brakes in predetermined order to cause the latter to halt the rotation of said spindles, a drive for moving said belt relative to said spindle, a timer for periodically starting said drive, and a limit switch actuated by said traveller for stopping said drive.

11. In a device for simultaneously winding a plurality of yarn packages, the combination with a plurality of spindles for supporting and rotating the yarn packages and a spindle brake for each spindle, of an endless belt positioned to pass adjacent to said spindles, a traveller fastened to said belt for operating on said spindle brakes in predetermined order to cause the latter to halt the rotation of said spindles, a drive for moving said belt relative to said spindle, a timer for periodically starting said drive, and signal means for indicating that the drive is started.

12. In a device for simultaneously winding a plurality of yarn packages, the combination with a plurality of spindles for supporting and rotating the yarn packages and a spindle brake for each spindle, of an endless belt positioned to pass

adjacent to said spindles, a traveller fastened to said belt for operating on said spindle brakes in predetermined order to cause the latter to halt the rotation of said spindles, a drive for moving said belt relative to said spindles, signal means for indicating that the drive is started, an interval timer, warning means operated by said interval timer for indicating that the textile apparatus is not attended, a timer for periodically starting said drive and energizing said signal means and said interval timer, and manually operable means for preventing the operation of said warning means.

13. In a device for simultaneously winding a plurality of yarn packages, the combination with a plurality of spindles for supporting and rotating the yarn packages and a spindle brake for each spindle, of an endless belt positioned to pass adjacent to said spindles, a pair of travellers fastened to said belt at points spaced apart a distance equal to one-half the length of said belt, said travellers operating on said spindle brakes in predetermined order to cause the latter to halt the rotation of said spindles, a drive for moving said belt relative to said spindles, signal means for indicating that the drive is started, an interval timer, warning means operated by said interval timer for indicating that the textile apparatus is not attended, a timer for periodically starting said drive and energizing said signal means and said interval timer, manually operable means for preventing the operation of said warning means, and a limit switch actuated by said traveller for stopping said drive when said traveller has passed said spindles.

14. In a device for simultaneously winding a plurality of yarn packages in which the feed of yarns to the winding apparatus is continuous, the combination with a plurality of spindles for supporting and rotating the yarn packages about a stationary axis of rotation and a spindle brake for each spindle, of automatic means for operating on said spindle brakes in predetermined order to cause the latter to halt the rotation of said spindles.

15. In a device for simultaneously winding a plurality of yarn packages in which the feed of yarns to the winding apparatus is continuous, the combination with a plurality of spindles for supporting and rotating the yarn packages, each spindle having stopping means for halting the rotation thereof, actuating means movable successively to a series of operating positions, at each of which said actuating means operates on a stopping means to cause the latter to halt the rotation of a spindle, and automatic means for moving said actuating means successively to said operative positions in predetermined order.
